INSTALLATION FOR FULLY AUTOMATIC OPERATION IN LAUNDRY AND OTHER PHYSICO-CHEMICAL PROCESSES, MAINLY FOR WASHING MACHINES

Emile D'Hooge, Ghent, Belgium, assignor to Ateliers de Construction Emile D'Hooge S.P.R.L., Ledeburg, Belgium

Filed May 2, 1960, Ser. No. 26,273

Claims priority, application Belgium May 12, 1959
5 Claims. (Cl. 200—38)

The tendency toward automatic operation in all kinds of technical industrial processes, and mainly in the chemical and technological industries is gaining more and more ground. This extension of automatism does not only tend to liberate a considerable labor force for more highly skilled duties, but also leads to considerable progress through the elimination of uncertainties resulting from the human factor, which fact makes it possible to conduct a process in a faultless way and in a manner which is reproducible at any time, according to definite data which have been carefully determined by previous theoretical and experimental analysis. These considerations also apply to the industries which deal with the treatment of textiles and, among others, to laundries and similar concerns, so that here too an effort has been made for designing devices capable of ensuring fully automatic regulation. On account of their very nature, these industries will most of the time have to deal with a large variety of products and articles which all need special treatment, so that the machines and their operation must be designed in view of a possibility of quick and easy change-over from one automatic process to another which must follow an altogether different course. It is moreover highly desirable that the number and the variety of various processing programs which can thus be established be as large as possible.

In laundry processes for instance, the first treatment consists in letting the linen soak some time either in cold or in tepid water in order to dissolve the stains caused by albuminoid substances such as blood. This is followed by one or more washing operations with various products. According to whether the linen is more or less soiled, the liquid used for the washing must be replaced a certain number of times in order to avoid that the dirt which it contains should settle again onto the linen. The actual washing is followed by a rinsing process the object of which is to clear the linen of the washing products and of the dirt which is still contained therein. Most of the time, this is done first with warm water, then with cold water, the number of rinsing baths needed amounting to four or more. While linen must moreover be bleached, with sodium hypochlorite for instance, and then blued, usually with ultra marine blue, this to compensate for a certain yellowing of the linen caused by the washing process and to thus give the linen a fresher aspect.

In mechanized laundries, all these operations are performed in a single machine, the complete process taking between 30 and 60 minutes for white linen and from 35 to 45 minutes for coloured linen.

This example shows that in such processes a certain number of treatments of different length have to be applied, using various chemicals.

The object of the present invention is to design, in view of such like processes, an installation by means of which it will be possible to perform the entire process in an altogether automatic way.

In order to be able to perform its work altogether automatically, the machine must be provided with devices

2

for introducing into and removing from the bath the necessary liquids and chemicals, as well as with means for keeping at all times the bath at the required temperature. For actuating aforementioned devices, provision must also be made for a system of programming which will determine the number, the order and the duration of the successive phases of the treatment, and for operating the various means used in each one of these phases.

10 If various duties must be performed by one and the same installation, such as that of treating a variety of articles, and/or treating the same kind of articles in different ways, the system of automatic programming must make it possible to preadjust the duration of successive phases and of the whole process, as well as the various treatments which are specific for each phase and the amount of products to be introduced at the proper time.

This however complicates matters considerably, considering that for each one of the successive phases it is not only the kind and amount of product to be added which has to be determined, but also a combination of operations each one of which can be chosen from a given number of possible operations.

15 It may be needed for instance, in the course of one particular phase, to renew the bath before adding another product, whereas in another phase such renewal is not necessary and it will do to add the new product to the old bath. On the other hand, the amount of liquid in the washing trough and its temperature may have to differ from one phase to the next.

20 On account of the very nature of this kind of business, and due to the fact that the staff employed therein is practically ignorant of anything concerning mechanics and electricity, it is an essential requirement that the setting of the controls be extremely simple to perform and devoid of any special difficulty, to which must be added the further imperative requirement that a wrong setting of some control or other must on no account lead to disaster. The installation must moreover be absolutely reliable and be built so as to resist not only the corrosive action of certain gases and vapours, but also a certain amount of rough treatment.

25 For ensuring smooth and troublefree working, some measure of visual checking must also be provided which will make it possible to ascertain at a glance:

30 (1) The nature and duration of each of the successive phases of the running process and,
(2) The time which has elapsed since the beginning of the process in question.

35 These facilities are especially of great importance when experimenting with a new process or the use of the new products. It follows therefrom that a possibility should be provided for interfering manually with a predetermined and preadjusted program, by extending, by shortening, by repeating or by omitting one or several phases.

40 Finally, another aim to be attained is to design the whole of the controlling devices as a single compact unit which can be quickly and easily fitted and connected to existing washing machines.

45 All these conditions are fulfilled by the controlling mechanism to which the preference has been given in the present invention and which is characterized by the fact that it comprises at least: a part which, during normal operation, moves with uniform speed; a distributing device comprising a certain number of fixed switching points, and also coupling devices which can be fitted in such way to or onto aforesaid part which moves with uniform speed, that this part is temporarily connected at certain predetermined time intervals to aforesaid distributing device in order to move the latter to its next switching point.

50 Aforesaid distributing device is connected in such way

to the devices which control the process, that in each one of its positions a predetermined combination of aforesaid controlling devices, corresponding to the particular process which has been chosen, is being operated in a predetermined order.

The distributing device may be either a pneumatic or hydraulic system, so that the devices controlling the process are themselves operated either pneumatically or hydraulically, but preference is given however to an electric switching device by means of which the various devices can be operated electrically or electro-magnetically. In the same way, the coupling between the part which moves with uniform speed and the distributing device can be operated by electrical, pneumatic or hydraulic means, as well as in a purely mechanical way.

According to another characteristic feature of the present invention, one or more further switching devices are inserted in the trajectory of the coupling devices, so that, during the time interval in which the part moving with uniform speed is coupled to the distributing device by means of one of the coupling devices, the actual coupling device actuates simultaneously one or several of aforesaid auxiliary switching devices. To this effect, use can be made of distinct coupling devices of various forms and dimensions which, when they act as coupling elements, operate various combinations of aforesaid auxiliary switching devices, in accordance with aforesaid forms and dimensions. Preferably, one of these auxiliary switching devices is being operated while the distributing device passes to its next position, and this as long as the switching operation lasts, aforesaid switching device then acting in such way on the controlling device that the latter is rendered inoperative during this time. One or more of the further switching devices which may or may not be operated during the travel of the distributing device, this operation or non-operation depending on the shape and the dimension of the coupling devices being used, can be made to control certain operations, such as the emptying of the washing trough, which, if they must be performed, must be finished before the beginning of a new phase of the treatment. Finally, one of aforesaid auxiliary switching devices can be used for ending the whole process and, if found desirable, for switching-on an acoustic warning signal.

According to another characteristic feature of the present invention, the distributing device is coupled to the controlling system through a program selector by means of which it is possible to pre-set at will, the various controls which must be operated in each position of the distributing device, according to the requirements of the goods which are being treated.

For easy introduction of the necessary chemicals, the machine conforming to the present invention, is fitted with a funnel of corrosion-free material, connected to the washing trough and on top of which there is a set of small containers for the various chemicals, which containers can be tipped-over by means of an electro-magnetic trigger so as to pour their content into the funnel.

Aforesaid characteristic features, as well as numerous constructional features of the installation conforming to the present invention, will appear more clearly from the description of an embodiment, given below by way of example with reference to the appended drawings, of which:

FIG. 1 is a simplified, diagrammatic perspective view of a complete machine, such as a washing machine, to which the control system conforming to the present invention has been applied and connected;

FIG. 2 represents on a larger scale a perspective front view of the switchbox with timing device and program selector, which is part of the controlling device conforming to the present invention;

FIG. 3 is a cross-section of the timing device with the distribution device and the auxiliary controlling devices;

FIG. 4 is a front view representing in a very much

simplified way, the constant speed timing disc for adjusting the duration of successive phases, part of the edge of aforesaid disc having been omitted for illustrating the way in which the plugs screwed into this disc work in conjunction with the distributing device and the auxiliary controlling devices;

FIG. 5 is a diagram explaining the setting of the program selector, showing by way of example, a given program for a washing cycle encountered in actual practice;

FIG. 6 shows, but in a still simpler way, the disc represented in FIG. 4, onto which an indicating dial has been fitted, which dial is divided into sectors corresponding to the position of the various coupling devices and mention at the same time the succession of phases such as they have been set according to the program represented in FIG. 5;

FIG. 7 is a side view of a diagrammatic representation of the controlling system conforming to the present invention, showing at the same time the inlet and outlet pipes and valves, as well as the pneumatic operation of the latter, and the funnel with the cups for chemicals mounted on top;

Finally FIG. 8 is a wiring diagram of the electrical part of the controlling device.

FIGURE 1 shows by way of example a washing machine to which has been fitted a system conforming to the present invention for automatically controlling the washing process according to a pre-set program. As shown in this figure as well as in FIG. 7, this installation comprises a switching box 1 onto which is also fitted the setting disc 2 for adjusting the duration of the successive phases of the process, as well as the program selector 3 and the funnel 4 for introducing the chemicals, connected by a pipe 6 to the bottom of the outer trough of the washing machine.

Above the funnel 4 which is made of some corrosion resistant material, such as stainless steel or plastics, but preferably of galvanized sheet iron, there are several (six on the figure) small cups 5 made of plastics and mounted on pivots supported by Bakelite brackets and into which, at the beginning of each washing process, the various chemicals are introduced which will have to be added in succession to the washing bath during the various phases of the process. Each of these cups is normally kept in equilibrium by a locking device which can be released by an electro-magnet 7 so as to tip over and thus pour its contents into the funnel. Each time when one of these cups is tipped and thus pours its contents into the funnel, a certain amount of water is made to flow into the latter so as to wash away the chemical in question and to introduce it into the washing trough. Each one of these electro-magnets 7, marked in FIGS. 7 and 8 by the Roman figures I to VI, can thus, as will be explained in fuller detail below, be operated individually at predetermined times by the program selector working in conjunction with the setting disc so as to introduce at the proper moment the required amount of chemicals into the cycle, aforesaid products being referred to by the same corresponding Roman figures in FIG. 5.

As shown more particularly in FIGURE 7, the washing machine comprises a cold water inlet 8, a warm water inlet 9 and a steam inlet 10, each of these inlets being also controlled by a valve 11—12—13 respectively. Each of these valves is in turn operated by compressed air via the pipes 15—14—16 respectively each of which is controlled by a three-way cock 18—17—19 respectively operated by electro-magnets, also shown in the diagram of FIG. 8. The drain pipe 20 of the machine is normally kept closed by the compressed air cylinder 21, connected by a pipe 22 controlled by a three-way cock 23 actuated by an electromagnet, to a source of compressed air which has not been represented. When the exciting current which controls aforesaid three-way cock 23 is switched on, the latter releases the air from the pressure cylinder 21, which causes the drain pipe 21 to open rapidly. As soon

as the exciting current of aforesaid electro-magnet is switched-off, the three-way cock 23 returns to its original position, the result of which is that pipe 22 is again put under pressure and that aforesaid drain opening 20 is closed.

In order to adjust the liquid level in the washing tub, the machine is also provided with a float controlled device 24 connected to aforesaid washing tub by pipe 36 and fitted in such way that it is possible to adjust the amount of liquid contained in the tub to two different levels. Float 25 is fastened to the end of the float rod 26 which carries two stop rings 27 and 28 respectively, which rings can be set for adjustment of the lower level and of the higher level respectively. Aforesaid stop rings work in conjunction with a lever 29 pivoting at 30, so that when the float has come down to the lower level, stop 27 pushes down lever 29, causing the latter to operate a micro-switch 32 mounted below the lever, whereas when the upper level has been reached, it is stop 28 which acts on the latter and pushes it upwards, thus operating a micro-switch 31 mounted above aforesaid lever.

This same FIG. 7 also shows in a very diagrammatic way, thermostatic switches 33, 34 and 35 located in the washing tub of the machine, aforesaid thermostats being set to different temperatures of 40°, 60°, 90° C. respectively for instance, i.e. in such way that the contacts marked by the same figures in FIG. 8, close as soon as the temperature of the bath exceeds 40°, 60°, 90°, respectively.

Thus, the washing machine which has been chosen by way of example for illustrating an embodiment of the present invention, is provided with all the necessary controls for ensuring automatically the regular course of a complete washing cycle in a number of predetermined phases of predetermined durations, the addition of the various washing products, the introduction of either cold or warm water, the heating by steam to a predetermined temperature and the emptying of the washing tub, all according to a definite pre-set program.

This does not exclude numerous further possibilities which are all comprised within the scope of the present invention. So for instance it is possible to use other means of compression than compressed air, to design an electrical control by means of servo-motors or otherwise, or also a direct control by purely mechanical means. It is evident on the other hand, that the various devices which have been mentioned above may differ with respect to their shape, their dimensions and their relative positions as represented in the figures.

The following account will comprise a description of the various means used for actuating aforementioned controlling devices according to a definite pre-set program. This account will be based on an example of embodiment which offers the following possibilities:

Maximum number of phases included in the treatment:

10.

Full time taken by a complete cycle: max. 60 minutes.

Shortest time interval: 1 minute.

At the end of each phase, the control is stopped for a length of time of approximately 45 seconds.

During this stop, the user is given free choice between the following alternatives:

- (1) Leaving the bath as it is,
- (2) Draining the bath,
- (3) Terminating the whole process and switching-on an acoustic warning signal.

In each one of the phases of the process, there is a choice between the following possibilities:

- (a) Cold or warm water.
- (b) High or low level in the tub.
- (c) No steam heating, or steam heating up to 40°, 60° or 90° C.
- (d) Six different washing products (I . . . VI).

On the other hand, it will be appreciated that for

other physico-chemical process to which the system conforming to the present invention can also be applied, quite a number of other combinations and possibilities can arise, which can however be controlled in an altogether similar way according to a definite pre-set program.

The mechanism used for adjusting the duration of the successive phases of the process, i.e. the timing device which is partly visible in FIGS. 1 and 2, is represented separately in vertical cross-section in FIG. 3. This mechanism comprises first of all a driving device revolving at a predetermined constant speed, such as synchronous motor 37, connected by a worm gear 38—39 to a shaft 40 revolving in a fixed bearing 42. The rotational speed of the motor, as well as the reduction ratio are calculated in such way that aforesaid shaft 40 makes one complete revolution in a predetermined time equal to the longest duration of a complete washing process, i.e. in exactly sixty minutes in the present illustrative example. Near its other end, aforesaid shaft 40 carries a part 2, generally shaped as a circular disc, which can turn loosely on this shaft but can also be rigidly connected to the latter when it is clamped between a knurled nut 44 screwed onto the end of the shaft, and a flange 45 fastened to the shaft. Aforesaid disc-shaped part, i.e. the setting disc 2 which is also represented in FIGS. 1 and 2, has near its circumference a certain number (sixty in this particular instance) of equally spaced tapped holes 46 whose centers lie on a circumference which is concentric with the axis of the disc. As in this particular example one complete revolution of the shaft is effected in sixty minutes, it is self-evident that the interval comprised between two adjacent holes will be travelled-through exactly in one minute.

Plugs 47 can be introduced and fastened into aforesaid holes 46, for instance by screwing, so that, while the disc 2 is turning, these plugs come successively into contact with a small sprocket wheel 48 provided with as many teeth as there are phases in the complete process, i.e. ten in this particular instance. Aforesaid plugs act in such way on the small sprocket wheel that the latter moves exactly by one tooth at each passage of a plug.

Immediately below and behind the small sprocket wheel 48, the actuating parts of one or more micro-switches 49, 50, 51 mounted one behind the other are located in the path of aforesaid plugs 47. The coupling between disc 2 and the sprocket wheel 48 is effected by means of dissimilar plugs which, according to their length, actuate during their transit and whilst engaging the sprocket wheel in question, one, two or three of the micro-switches. For easy identification of the plugs of different lengths, the latter are provided in front i.e. on their heads, with clearly visible markings, being for instance painted in different colours. As will be explained in the description given below, the short plugs which only come into contact with micro-switch 49, merely disconnect the controlling device during the transit from one phase to the next; the plugs of medium length, which come into contact with the two micro-switches 49 and 50, also trigger the drainage of the bath, whereas the long plugs furthermore control the devices which stop the whole washing process and give rise to an acoustic warning signal. The small sprocket wheel 48 is fastened to the shaft 52 of a ten position switching or distributing device which, in this particular instance, consists of a small fixed base plate 53 of some insulating material, carrying concentrically to the shaft 52, on the one hand a continuous slip ring 54, see FIG. 4, and on the other hand a circle of mutually insulated contact studs 55. A contact bloc or arm 56 fastened to shaft 52 carries two brush-holders 57—58 fitted with spring-loaded carbon brushes 60—61 respectively, of which one (viz. brush 61) is kept into contact with the slip-ring 54, whereas the other (viz. brush 60) comes successively into contact with each one of the contact studs 55 corresponding to one of the ten positions of the distributing device. The contact arm 56 is made of insulating material, while the two carbon brushes 60 and 61 are

connected electrically together by any suitable means which need not be described, so that when the little sprocket wheel 48 has made one complete revolution, the slip ring has been put in succession into contact with each one of the separate contact studs arranged on the outer circumference. The angular position of contact arm 56 with respect to the little sprocket wheel 48 is such that brush 60 is each time centered exactly onto one of the contact studs 55 before and after one of the plugs 47 has been moving the sprocket wheel 48 by one tooth.

As during the rotation of the small sprocket wheel there is always at least one of the micro-switches 49—50 and 51 which is actuated, the electrical connection can be made as follows: as can be seen in the wiring diagram of FIG. 8, during the whole displacement of brush 60, the transit from one contact stud 55 to next is performed in the absence of current, thereby preventing all sparking.

By unscrewing nut 44, the setting disc 2 can be made free of shaft 40, after which aforesaid disc can be displaced by hand independently of the timing device, which is effected by means of a nut 62 screwed onto a projection of aforesaid disc, this nut serving at the same time to clamp a cover 63 of some transparent material onto the setting disc 2. Between aforesaid transparent cover 63 and aforesaid disc 2, a dial made of cardboard or of some similar material can be clamped, this dial having previously been subdivided, by drawing or otherwise, into sectors as is represented in particular in FIG. 6, this division corresponding to the position of the plugs in the peripheral holes and thus giving a visual indication of the way in which the duration of the successive phases of the process has been adjusted. It may be convenient moreover to provide the various sectors of the dial with a summary indication of the various operations which take place during the various phases. Such indicating dials can be prepared and printed beforehand for the most current processes, and handed over to the user.

The selection of the various components of each of the ten possible phases of the process is made by means of the program selector 3 which, as shown more clearly in FIG. 2, comprises a number of switches arranged in ten rows and eleven columns in the instance chosen for this example. The switches of each row belong to the corresponding phase of the process, whereas the switches of a same column are all connected with a same function. This is represented diagrammatically in FIG. 5, where the first column refers to the hot water supply, the second column to the highest level of liquid in the washing tub, the third, fourth, and fifth columns to the steam heating to temperatures of 40°, 60° and 90° C. respectively, and columns 6 to 11 to the six different chemicals contained in the little cups mounted on top of the funnel. It should be noted at this time, that this diagram is designed in such way that if the switch which controls the hot water supply is not switched-on, only cold water will be supplied until the predetermined level has been reached, whilst if aforesaid hot water switch is "on," the cold water supply is cut-off. Similarly, it is always the lower level which applies unless the switch controlling the higher level is "on."

All these switches are single pole. All switches in a same column are connected by one of their contacts and over a common lead to the controlling device corresponding to their function.

When a row of switches must be switched-on, i.e. at the beginning of the phase corresponding to that row, a voltage is applied to the other contact of each one of these switches by means of a relay which closes its contacts during this particular phase. The switches of columns 1 to 5 each have been their own pair of contacts at the relay belonging to their own row, whereas the switches of the six remaining columns, which refer to the introduction of the six chemicals, have altogether only one pair of contacts at the relay belonging to their row. The result of this disposition is that as long as the relay of

one particular row is not switched-on, the five first switches of aforesaid row are mutually independent. This is necessary in order to avoid that two or more of the vertical control leads, each of which is in a measure to actuate a control device, might be interconnected in a permanent way, which could give rise to the drawback that the corresponding controlling functions would always be effected together even when this is not required. So for instance, if in the course of operation 1 the first and second switches were combined, and if in operation 4 the second and third switches were combined, the result would be that in both cases in a combination of the functions corresponding to the first, second and third switches would be obtained. This same precautionary measure is however not strictly needed in the six last columns, considering that, in a general way, not more than one chemical will be added in the same phase, so that there will never be more than one of the switches which will be "on" in each row. However, if on account of the design of the mechanism for introducing the chemicals or of the particular nature of the physical process, the necessity should arise in certain cases to actuate several times a given controlling device, each time in combination with another controlling device, the necessary devices should also be provided here for preventing that the contacts of each row be mutually disconnected by means of individual pairs of contacts at the relay belonging to that row.

After all, it is not necessary to provide a complete set of switches in each row. If a switch is omitted here and there, and more particularly in the columns referring to the chemicals, as shown for instance in FIGS. 2 and 5, the possibilities of combination are certainly limited thereby, but this will generally not prove to be a serious handicap in practice.

FIGURE 5 shows in a diagrammatic way, the position of the switches in connection with a practical washing process, while FIG. 6 shows the corresponding positions of the plugs 47 on the setting disc 2. FIGURE 6 also shows the indicator dial which has already been mentioned and which is divided into sectors each of which bears a brief indication of the operation being performed at the time. This setting corresponds to the following program:

no.	Operation		Water supply	Level	Steam supplied up to, ° C.	Chemical	Time in Minutes
	name	no.					
1	Soaking		Cold	High	40	I	
2	1st lather		Warm	Low	60	II	10
3	2nd lather		Warm	Low	90	III	15
4	Rinsing		Warm	Low			3
5	Bleaching		Cold	High		IV	5
6	Rinsing		Cold	High		V	2
7	Rinsing		Cold	High			2
8	Blueing		Cold	High		VI	3
9	Stop						50
10	Stop						10
							60

Most of the time, numerous processes such as the one to which the above table refers, will take less than 60 minutes. In order to make it possible to start a new cycle as soon as the preceding one, which lasted only 50 minutes, is finished, the last part of rotation corresponding to the sector marked "stop" in FIGURE 6, must be travelled through at an accelerated rate. This can be obtained, as was already described above, by disconnecting the setting disc from the driving shaft and then moving it by hand. Although, as in the present example, the complete process comprises less than ten phases, it is necessary all the same to always insert ten plugs into the setting disc, because, when the latter has made one complete revolution, the distributing device will also have returned to its original position. The plugs which are not needed for the process which is being carried-out,

can be screwed into any of the holes of that part of the disc which is not being used.

The operation of the installation which has thus been equipped, will now be described in detail with reference to the diagram of FIG. 8. This diagram embraces the following controlling devices which have already been mentioned: the valves 18, 17, 19 for controlling the cold water, the warm water and the steam supply respectively; the float contacts 31—32 respectively for high and for low levels in the washing tub; the thermostatic contact devices 33, 34, 35; the electromagnets 7 which control the cups containing the chemicals; the synchronous motor 37; the micro-switches 49, 50 and 51 of which the one marked 49 operates at each passage of one phase to the next, whilst the two others can only be operated by plugs of sufficient length; and finally the ten-position distributing device 54—55 actuated by the setting disc by means of aforesaid plugs. The diagram in question also embraces the following auxiliary items: the main transformer VT₂; the bell transformer t₂ to which is connected a generator of acoustic signals; a main switch h; a door- and safety-switch d; the auxiliary relays R1, R2, R3, R4, each fitted with one or more contacts marked respectively r₁, r₂, r₃, r₄; the auxiliary relays C1, C2, . . . C10, each one of which is associated with one of the positions of the distributing device and thus also with one of the rows of the program selector, whereby one of them, (viz. C3) is represented in FIG. 8 with all its contacts. In order to facilitate the reading of this diagram, the contacts have most of the time not been represented near the coils but located at convenient places in the circuit; the meaning of the symbols used for these contacts should be noted; all contacts which are normally open are represented by two short parallel lines, whereas the contacts which are normally closed are represented by two short parallel lines, themselves crossed by a short oblique line.

For starting the machine, the first thing to do is to close the main switch h, and then to make sure that all doors fitted with a door contact are properly closed. If everything is in order in that respect, the voltage supplied at the output terminals L1 and L2 of the mains transformer VT₂ will be applied through switch h and contact d, the normally closed contact of micro-switch 51 and the normally closed contacts r₁, r₂, r₃ to the synchronous motor 37 which thus begins to run. This same voltage is also applied through the normally closed microswitch 49 and the distributing device 54—55, which at this instant is in position 1, to relay C1 whose armature is thereby attracted and closes its contacts. Thus, the combination of controlling functions needed for phase 1 of the process has been established. If it be assumed that for this first phase none of the switches are closed, this will however not prevent valve 17 which controls the cold water supply to be operated through a normally closed contact r₂, provided that the float contact 32 is closed, i.e. provided that the float is still lower than the predetermined lower level.

Connected in parallel with the device 17, there is an auxiliary relay R1 to which the voltage is thus also applied and which opens its contact r₁. This stops the synchronous motor as well as the rotation of the setting disc as long as the filling lasts, so that the time used for filling the tub does not count for the determination of the duration of the phases. The same applies if it is the warm water supply or the steam supply which is opened instead of the cold water supply.

As soon as the required level has been reached, so that lever 29 (FIGURE 7) is no longer held downward by the stop-ring 27, microswitch 32 returns to its position of rest, the addition of cold water ceases and relay R1 is released, which starts the synchronous motor again.

When the predetermined time for the first phase has elapsed, or in a general way, when a phase has come to an end, it is first of all microswitch 49 which is actuated by the plug 47 in operation at the time. This causes relay

C to release, thus cutting-off the current supply of the switches belonging to the corresponding row of the program selector, as well as the controlling devices connected to these switches. If the plug in question was a short one, nothing else happens until, after a time interval of approximately 45 seconds, the distributor has passed onto its next position and switch 49 has come back to its starting point. If the plug was one of the medium length, a voltage is also applied by microswitch 50 to the valve 23 which controls the drainage, so that the washing tub is emptied in a very short time, after which the next phase of the process can begin.

If when one of the relays C is energized through a closed switch in the corresponding row, this closes the actuating circuit of device 18 which controls the addition of hot water, so that clean hot water will be fed into the processing tub at the same time that relay R2 connected in parallel with the device 18 will be energized, the result being that: (1), the synchronous motor 37 is stopped and (2), the device 17 which controls the admission of cold water is thereby locked. This condition lasts until the liquid level in the processing has reached the lower predetermined level. If it is the second switch in the row which has been closed, it is relay R4 which will be energized, thus causing contact r₄ to close. The circuit controlling either the cold water or the warm water inlet then no longer depends on microswitch 32, but on microswitch 31 instead, so that the inflow is not cut-off before the level in the processing tub has risen sufficiently for switch 31 to be actuated by the stem of the float.

When one of the switches in the third, fourth or fifth column is closed, current flows through the thermo-contacts 33, 34 or 35 to the device 19 controlling the admission of the steam, which at the same time brings relay R3 into action, so that as long as steam is admitted, the synchronous motor is at a standstill while aforesaid inlet of steam goes on until the processing bath has reached the required temperature and the thermostatic switch opens. If two of the three switches close their contacts at the same time, it is evident that it is the higher of both corresponding temperatures which must be reached before the supply of steam is cut-off, apart from which fact aforesaid inflow of steam depends on the position of microswitch 32, it being understood however that this inflow cannot take place if the liquid contained in the processing tub has not reached at least the lower predetermined level.

When one of the switches in the six columns referring to the addition of chemicals is closed, the corresponding electro-magnet 7 is energized and the contents of the cup associated therewith is poured into the funnel. This also can not take place however, at least as far as the chemicals IV, V and VI are concerned, unless the liquid contained in the processing tub has reached at least the lower predetermined level.

When at the end of the processing phase, a long plug 47 actuates simultaneously microswitches 49—50 and 51 the current supply to the synchronous motor 37 is cut-off, whereas voltage is applied to the bell transformer t₂, with the result that the device "S" emits an acoustic signal until the main switch h has been opened.

What I claim is:

1. A timer device for timing the operation of a number of relay controlled devices, said device comprising a disc having a plurality of circumferentially spaced holes, coupling elements carried in some of said holes, means rotating said disc at a constant speed, a group of switches, means supporting said switches alongside said disc in a position wherein said switches lie in the path of movement of said coupling elements for actuating said switches, another switch having a rotary arm element, a plate, means supporting said plate in a fixed position alongside said rotary arm element, said plate containing a slip ring concentric with the axis of rotation of said rotary arm element, and a plurality of circumferentially spaced contacts

disposed radially outwardly of said slip ring, a conductor brush carried by said rotary arm element and continuously engaging said slip ring, another conductor brush carried by said rotary arm element and adapted to engage said contacts, a toothed sprocket wheel operatively connected to said rotary arm element, means supporting said sprocket wheel adjacent said disc in a position wherein the teeth on said sprocket wheel lie in the path of movement of said coupling elements whereby said coupling elements engage said teeth for rotating said sprocket wheel, a source of electricity, a plurality of controlling relays, means electrically connecting said brush conductors to each other and to said source, and means electrically connecting each of said contacts with a different one of said controlling relays.

2. A time device in accordance with claim 1 wherein each of said controlling relays includes a plurality of make contacts which are connected to said source by means of another manually actuated make contact.

3. A timer device in accordance with claim 2 wherein said manually actuated make contacts are arranged in a plurality of rows and columns, the contacts in each row being connected to the same controlling relay, the contacts in each column being connected to the same controlled device.

4. A timer device in accordance with claim 2 wherein

5 at least one switch of said group of switches is actuated during each movement of the second-mentioned brush conductor from a position of engagement with one of said contacts to a position of engagement with the next succeeding contact, said switch having a make contact which is connected to said source and to the make contacts of each of said controlling relays.

10 5. A timer device in accordance with claim 2 wherein said controlling relays are connected to said contacts in such manner that said controlling relays are operated in predetermined sequence.
